UNITED STATES PATENT OFFICE.

FRANK R. BUSSERT, OF CHICAGO, ILLINOIS.

DESIGN FOR AN ADVERTISING-CLOCK.

57,310.

Specification for Design.

Patented Mar. 15, 1921.

Application filed March 13, 1920. Serial No. 365,665. Term of patent 14 years.

To all whom it may concern:

Be it known that I, FRANK R. BUSSERT, a citizen of the United States, residing at Chicago, Illinois, in the county of Cook and State of Illinois, have invented a new, original, and ornamental Design for Advertising Clocks, of which the following is a specification, reference being had to the accompanying drawing, forming part thereof.

The figure is a plan view of an advertising clock, showing my new design.

I claim:

The ornamental design for an advertising clock, as shown.

FRANK R. BUSSERT.

Witnesses:

P. R. LUND,
MARIE NAGEL.
